UNITED STATES PATENT OFFICE.

DAVID C. KLAUSMEYER, OF CINCINNATI, OHIO, ASSIGNOR TO THE CINCINNATI BICKFORD TOOL COMPANY, OF CINCINNATI, OHIO, A CORPORATION OF OHIO.

SLEEVELESS REVERSING CLUTCH.

1,418,805.

Specification of Letters Patent. Patented June 6, 1922.

Application filed June 14, 1921. Serial No. 477,511.

To all whom it may concern:

Be it known that I, DAVID C. KLAUSMEYER, a citizen of the United States, residing at Cincinnati, in the county of Hamilton and 5 State of Ohio, have invented a new and Improved Sleeveless Reversing Clutch, of which the following specification is a full disclosure.

This invention relates to frictional reversing mechanism useful in connection with various machines and its primary object is to render available a structure characterized by extreme simplicity and compactness.

This invention also contemplates the employment of a closed casing within which is contained all of the various working elements so mounted and arranged as to admit of being readily assembled and the invention also embodies simple means whereby the 10 gears may be maintained with precision in their correct meshing relation and whereby adjustment for wear may easily be made by merely replacing certain bushings; the various parts being demountable to facilitate 15 the replacement of the bushings.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a longitudinal section showing 40 the relations of the various elements. Fig. 2 is an end view looking towards the left of Fig. 1. Fig. 3 is a section through line 3—3 of Fig. 1 showing the means for manually shifting the clutch actuating collar. Fig. 45 4 is an end view, partly in section, of one of the clutches. Fig. 5 is a section through line 5—5 of Fig. 4. Fig. 6 is a section through line 6—6 of Fig. 1, and Fig. 7 is a section through 7—7 of Fig. 6.

50 The various working elements are mounted in a casing which is preferably enclosed so as to hold a bath of lubricant; such casing consisting conveniently of the two parts 1 and 2 suitably bolted together. The as-

sembled sections provide two end-walls 48 55 and 49 which are apertured to accommodate the shaft 11. The aperture in the end wall 48 is relatively large and permits the bushings 13 and 51 to be removed therethrough when the shaft is withdrawn. The shaft 60 is retained against axial movement by a shoulder 50 which bears against the washer-like portion 47 of the bushing 13 which is secured in the smaller aperture of the wall 59; the reduced end 12 of the shaft 11 being journaled within said bushing.

The other end of the shaft 11 is reduced, as indicated by 10, and is journaled within the bushing 51 which also has at its end a washer-like flange 14 bearing against a 70 shoulder 52 on the shaft so as to retain it in place. The bushing 51 is mounted within cap 3 which, by means of bolts 53 and position-screws 54, is adjustably secured to the outer face of the end-wall 48; thereby 75 determining the position of the flange 14 which, as will hereinafter be explained, cooperates with the flange 47 on the other bushing to limit the separation of the gears and hold them in correct mesh with the 80 bevel gear 43.

The motion may be transmitted to or from the shaft 11 by means of a pulley or other prime-mover 55 which, preferably, is journaled on the outer periphery of the sleeve-like portion provided by the cap 3. This pulley is shown secured to the shaft through the intermediary of a member 5 which is, by means of the screws 6, bolted to the hub 4 of the pulley. The member 5 is, in turn, keyed (as indicated by 7) to the end 9 of the shaft 11; a taper pin 8 being also used to prevent any end-play. The web of the pulley is provided with an aperture 40 through which access may be had to a cap 95 nut 39 which is screwed into the lower part of the casing and which may be removed for the purpose of draining the oil therefrom and for affording access to the clutches for purposes of regulation.

A hub 41 of the frame extends transversely to the shaft 11 and contains a bushing 42 within which is journaled the sleeve 44 of a common bevel gear 43. This gear is, by means of the feather 45, splined to the other transmission shaft 46 through which motion is conveyed either into or out of the casing, as the case may be.

Mounted appropriately directly on the shaft are two gear units which may be integral but which preferably consists of two parts, to wit: the gear proper and the friction element. This friction element is in the form of an annulus providing a ring 28 having a socket 27 upon its outer end; the inner periphery of the ring serving as a friction surface. This element is provided 10 with a sleeve 29 journaled loosely directly on the shaft 11 so that it may rotate freely on said shaft and so that it may have a slight axial movement to permit the pitch circles of the gears to be maintained correctly in coincidence when said gears are transmitting power, as will be explained.

The gears 30 and 31 may be, by means of screws 32, secured firmly to their respective friction elements so as to form therewith a 20 unitary structure; this arrangement permitting very high grade material to be used for the gears without materially increasing the expense of the construction, and also facilitating the cutting of the teeth. These 25 gears are conversely arranged, as shown, and are each simultaneously in mesh with the common gear 43 and, as will be understood, they accordingly will run in opposite directions. The motion, therefore, will be transmitted 30 in one direction or the other depending upon which one of the gears has been brought into a non-rotatable relation with the shaft 11. This is effected by one or the other of the two friction clutches which are 35 preferably constructed as follows:

A shoe-supporting block 15 is splined to the shaft 11 by means of a key 16; this block 15 being located within the chamber 27 and arranged between the gear 30 and the end 40 wall of the casing. The block 15 provides a sleeve which at 56 abuts against the friction element E; the position being maintained and regulated by the thickness of the flange 14 on the bushing 51. This block 45 provides an annular chamber 17 in which is located a brake shoe 18 non-rotatably secured thereto by means of a key 19. This brake shoe is of the expandable type and, when expanded, frictionally engages the inner 50 face of the element E and locks the gear 30 to the shaft 11. The brake shoe preferably is provided with a few grooves 27 for collecting dirt and containing lubricant, so as to keep the frictionally engaging faces in 55 good condition.

The expansion of the brake shoe is effected by a shiftable lever mechanism which, in the form herein shown, may consist of a taper pin 22 having its end 23 screw-threaded into 60 a floating lock-nut 24 which rides in a recess 25 provided by the block 15. A clamp block 57 is engaged by twin screws 58 and 59 so that the pin 22 may be secured positively in its adjusted position. The adjustment is effected 65 by removing the nut 39, which makes

the ends of the various screws accessible through the hole 40 in the pulley to a screw driver by slightly rotating the shaft.

A pair of twin levers 20 and 21 are eccentrically journaled on the taper pin 22 and 70 bear against the ends of the expandable shoe 18; the ends of said levers extending into a recess 17 provided by the friction element E. The shaft 11 has a segment removed in the vicinity of the twin levers so as to allow 75 the same to project slightly into the contour of the shaft and make provision for a swinging movement of said levers.

The means for actuating the aforesaid levers comprises a shaft 38 journaled in the 80 frame and terminating in an arm 37 having a shoe 36 riding in the groove of a spool 35 that is shiftably mounted on the shaft 11 so that when the shaft 38 is partially rotated by 85 hand, the spool will be shifted towards one or the other of the gears. This spool is attached to an elongated key 33 which slides in a keyway in the shaft so that its ends may pass through the bores of the members E. The ends of the key are tapered so that they 90 may slide the levers and effect a clamping of the brake shoe 18 as before described.

It will thus be seen that this invention proposes a very compact self-contained and rugged device well adapted for use wherever it is desirable to effect a stoppage or a reversal in motion.

Without further analysis, the foregoing will so fully reveal the gist of this invention that others can, by applying current knowledge, readily adapt it for various utilizations by retaining one or more of the essential characteristics of either the generic or specific aspects of this invention, and, therefore, such adaptations should be, and are 100 intended to be, comprehended within the meaning and range of equivalency of the following claims.

Having thus revealed this invention, I claim as new and desire to secure the following combinations and elements, or equivalents thereof, by Letters Patent of the 110 United States:—

1. A frictional motion-reverser combining a casing; removable journals positioned in the end-walls of said casing; a solid shaft non-translatably journaled in the journals in the end-walls of said casing and having one end protruding; means connected with said end to drive said shaft; a second shaft 115 extending through a side-wall of said casing; a bevel-gear affixed to the inner end of said second shaft and located closely to said first shaft; two bevel-gears in mesh therewith journaled on said first shaft, the outer 120 ends of said two gears each providing an annular recess, an expanding shoe arranged in each recess; two shoe-supporting blocks 125 slidably keyed to said shaft and arranged respectively at the outer ends of said two 130

gears in abutment with said journals; lever-means for expanding said shoes; a shiftable collar mounted directly on said shaft supporting said two gears; an elongated key 5 splined in said shaft and adapted to be translated by said collar to operate alternately said lever-means; and means for adjustably shifting one of said journals towards the other to take-up wear and maintain 10 the coincidence of the pitch-lines of said gears, said means being operable externally of said casing.

2. A frictional motion-reverser combining an enclosed casing having coaxial apertures 15 in its opposite end-walls, the one aperture being larger than the other; a removable bearing secured to the casing adjacent the larger aperture; a shaft journaled in said bearing and in the smaller aperture of the 20 end-wall of said casing and having one end protruding through said bearing, said shaft being bodily removable through the larger aperture; means connected with said end to transmit motion to or from said shaft; a 25 second shaft extending through a side-wall of said casing; a bevel-gear affixed to the inner end of said second shaft and located closely to said first shaft; two bevel-gears in mesh therewith and shiftably mounted on said first shaft, the outer ends of said two gears providing an annular recess; an expanding shoe 30 arranged in each recess; two shoe-supporting blocks splined to said shaft and arranged respectively at the outer ends of said two gears closely adjacent the end-walls of said casing; replaceable thrust-elements arranged between said blocks and the end-walls of said casing and adapted to limit the separation of said two gears under the pressures of the tooth intermesh; lever-means for expanding said shoes; a shiftable collar mounted on said shaft midway 35 of said two gears; and an elongated key splined in said shaft and adapted to be translated by said collar to operate alternately said lever-means.

3. A frictional motion-reverser combining an enclosed casing having coaxial apertures 40 in its opposite end-walls, the one aperture being larger than the other; a removable bearing secured to the casing adjacent the larger aperture; a shaft journaled in said bearing and in the smaller aperture of the end-wall of said casing and having one end protruding through said bearing, said shaft being bodily removable through the larger 45 aperture; means also journaled on said bearing and connected with said end to transmit motion to or from said shaft; a second shaft extending through a side-wall of said casing; a bevel-gear affixed to the inner end of 50 said second shaft and located closely to said first shaft; two bevel-gears in mesh therewith journaled on said first shaft, the outer ends of said two gears providing an annular recess, an expanding shoe arranged in each 55 recess; two shoe-supporting blocks affixed to said shaft and arranged respectively at the outer ends of said two gears closely adjacent the end-walls of said casing; lever-means for expanding said shoes; a shiftable collar 60 mounted on said shaft midway said two 65 gears; and an elongated key splined in said shaft and adapted to be translated by said collar to operate alternately said lever-means.

4. A frictional motion-reverser combining 70 an enclosed casing having coaxial apertures in its opposite end-walls, the one aperture being larger than the other; a removable bearing secured to the casing adjacent the larger aperture; a shaft extending into the 75 smaller aperture of the end-wall of said casing and having one end protruding through said bearing, said shaft being shouldered to prevent longitudinal movement thereof and adapted when said bearing is detached to be bodily removable through the larger aperture; a second shaft extending through a side-wall of said casing; a bevel-gear affixed to the inner end of 80 said second shaft and located closely to said first shaft; two bevel-gears in mesh therewith and shiftably mounted on said first shaft, the outer ends of said two gears providing an annular recess; an expanding shoe 85 arranged in each recess; two shoe-supporting blocks splined to said shaft and arranged respectively at the outer ends of said two gears closely adjacent the end-walls of said casing; replaceable thrust-elements arranged between said blocks and the end-walls of said casing and adapted to limit the separation of said two gears under the pressures of the tooth intermesh; lever-means for expanding said shoes; a shiftable collar mounted on said shaft midway 90 of said two gears; and an elongated key splined in said shaft and adapted to be translated by said collar to operate alternately said lever-means.

5. A frictional motion-reverser combining 95 an enclosed casing having coaxial apertures in its opposite end-walls, the one aperture being larger than the other; a removable bearing secured to the casing adjacent the larger aperture; a shaft arranged in said bearing and in the smaller aperture of the end-wall of said casing and having one end protruding through said bearing, a second shaft extending through a side-wall of said casing; a bevel-gear affixed to the inner end 100 of said second shaft and located closely to said first shaft; two bevel-gears in mesh therewith journaled on said first shaft, the outer ends of said two gears providing an annular recess, an expanding shoe, arranged in each recess; two shoe-supporting blocks 105 keyed to said shaft and arranged respectively at the outer ends of said two gears closely adjacent the end-walls of said casing; bushings arranged in said removable bearing and also in said smaller aperture, said bushings having portions intervening between the end-walls of said casing and said blocks to limit the end-play of said two 110 gears, said shaft and bushings being bodily 115

removable through the larger aperture; lever-means for expanding said shoes; a shiftable collar mounted on said shaft midway said two gears; and an elongated key 5 splined in said shaft and adapted to be translated by said collar to operate alternately said lever-means.

In witness whereof, I hereunto subscribe my name, as attested by the two subscribing witnesses.

DAVID C. KLAUSMEYER.
